REINFORCING JACKET FOR SOCKET SHELLS

Harvey Hubbell, Jr., Bridgeport, Conn., assignor to Harvey Hubbell, Incorporated, Bridgeport, Conn., a corporation of Connecticut

Application June 10, 1935, Serial No. 25,774

3 Claims. (Cl. 173—362)

This invention relates to new and useful improvements in electric sockets and has particular relation to the strengthening or reinforcing of sockets.

An object of the invention is to provide for the strengthening or reinforcing of sockets in a manner to prevent separation of the caps and shells of the sockets in shifting the socket on flexible mountings, and the invention also provides for the strengthening of the caps of sockets to prevent their being bent or collapsed during such shifting action.

Other objects and advantages will become apparent from a consideration of the following detailed description taken in connection with the accompanying drawing wherein satisfactory embodiments of the invention are shown. However, it will be understood that the invention is not limited to the details disclosed but includes all such variations and modifications as fall within the spirit of the invention and the scope of the appended claims.

In the drawing:

Fig. 1 is a side elevational view with parts broken away and showing a socket constructed and reinforced in accordance with the present invention;

Fig. 2 is a top plan view of the construction of Fig. 1;

Fig. 3 is a view similar to Fig. 1 but showing the strengthening jacket and ring as applied to a standard construction of socket;

Fig. 4 is a similar view showing the jacket and ring as applied to a socket having a reenforced cap; and

Fig. 5 is a detail sectional view taken substantially along the line 5—5 of Fig. 4.

An objection of socket shells now generally used is the weakness of the cap section which is usually made of thin metal. Such a cap is liable to yield or bend due to the leverage from the attaching nipple when the socket is shifted on flexible or adjustable supports, or due to weight of lamp shades, etc., mounted on the socket or lamp. Also, unless the detachable securing or locking means between the cap and shell are very accurately made the cap and shell are very apt to become separated in use, especially if a lateral pressure is applied to the shell. I have effectively overcome these objections in my new construction.

Referring in detail to the drawing and at first particularly to Figs. 1 and 2, a socket generally designated 10 is shown as including a metal shell 11 and a cap 12 the latter carrying a nipple 13 of any or the usual construction for attaching the socket to a suitable support. The shell 11 is of the usual construction, but the cap 12 is of heavier gauge metal than that ordinarily employed in the making of these caps, and may be

and preferably is of steel, although this last is not absolutely necessary since the purpose is to have the cap strong, particularly when it is equipped with a nipple connection, so that it will not bend out of place or collapse when a lateral pressure or leverage is applied to the shell, as for example when shifting the socket on a flexible mounting.

The lower portion of the shell 11 is of reduced diameter whereby a shoulder 14 is formed, and the cap 12 includes a portion 15 receiving the upper or inner end portion of the shell and at its upper side about its edge the cap is provided with a shoulder 16. The customary means for holding the cap and shell in assembled relation may be employed or may be omitted as desired. In the drawing the inner insulating linings for the cap and shell as well as the porcelain body, contacts, binding posts, etc., have been omitted. This shell 11 is a standard thin metal lamp socket shell, the upper portion above the shoulder 14, which comprises about one-half the length of the shell, being enlarged to receive the inside works of the socket comprising the insulating body carrying the switch mechanism when one is used, the binding post for connection of the lead wires and the various connections from the binding posts to the switch elements. The usual central and screw shell contacts are connected to the lower end of this body and the screw shell contact extends into the reduced lower portion of the shell below the shoulder 14. It is into this screw shell the screw contact on the lamp bulb is threaded.

According to the present invention the shell and cap are held together by means of a jacket 17 and a ring 18. The upper end portion of the jacket is of a diameter to receive the depending portion 15 of the cap and is externally screw threaded as at 19, while the lower portion 20 of the jacket is drawn inwardly or has its diameter reduced so that when the jacket is placed on the shell or the shell is inserted in the jacket the portion 20 of the latter will engage the shoulder 14 of the shell. It will thus be seen the jacket encloses the upper enlarged portion of the shell 11 and because the shoulder 14 is spaced below the upper end of the shell a considerable distance the support of the jacket 17 for the shell 11 is at a considerable distance from the lower end 15 of the cap embracing the upper end of the shell. There is therefore a considerable leverage advantage for the support of the shell by the jacket which obviously is much greater than that between the overlapping portions 15 and 28 of the cap and shell which must withstand all lateral bending when no jacket is used. It will thus be evident that with this jacket 17 there is much greater resistance to lateral bending and separation of a cap and shell than is possible where the

normal connection in the overlapped portions of the cap and shell only are relied on.

The ring 18 includes a portion 21 screw threaded in its inner side as at 22 and of a diameter to receive and be threaded onto the upper threaded end portion of the jacket 17. Also, the ring includes an inwardly extending upper flange-like portion 23 adapted to rest on the shoulder 16 of the cap when the cap is inserted into the ring 10 or the ring is dropped over the cap. Preferably the outer surface of the portion 21 of the ring is grooved or otherwise roughened as at 24 whereby the ring may be securely gripped for turning it.

15 To apply the jacket and ring to a socket to be strengthened or reinforced it is but necessary to place the jacket 17 over the shell of a socket and the ring 18 over the cap of the socket and then screw the ring and jacket together. This 20 will draw the reduced portion 20 of the jacket against the shoulder 14 of the shell and will also draw the flange-like portion 23 of the ring against the shoulder 16 of the cap securely locking the cap and shell together. Lugs 25 carried by the 25 cap enter into an opening or notch 26 in the jacket and thereby prevent relative turning of the jacket and cap. The opening, as shown, is enlarged providing a passage for the stem of a switch key although it will be clear that the passage 30 might be used for the guide for a pull chain, and it is also to be understood that the ring and jacket may be used in connection with a keyless socket.

It will be clear that when the cap and shell are 35 connected as here disclosed they may not be pulled apart or separated by any pressure or twist exerted on the nipple 13. Moreover since the cap itself is of heavy gauge metal, as of steel or the like, it will be clear that any ordinary pressure tending to bend or twist the nipple will not cause bending or collapse of the cap.

Fig. 3 shows the jacket 17 and ring 18 as applied to a socket of standard construction and including a shell 11 having its lower end portion 40 reduced to provide a shoulder 14 and having its upper edge portion fluted as at 28. The cap 29 carries a nipple 30 and receives the upper end portion of the shell 11 and has small pockets 31 to receive spring fingers 32 on the shell and which 45 catch in said pockets and against a shoulder 36 at the lower part thereof in the usual manner to connect the cap and shell. A comparison of Figs. 1 and 3 will show that the metal in the caps of standard construction, as in Fig. 3, is of a relatively light gauge of metal.

With the standard lighter construction of socket cap a bending action on the nipple 30 is apt to cause bending or collapse of the cap 29 or pull the cap away from the shell 11. When a 50 jacket 17 and ring 18 are disposed about this standard socket and screwed one onto the other the portion 23 of the ring is drawn downwardly onto a shoulder 33 of the cap and the portion 20 of the jacket is drawn against the shoulder 14 of the shell so that the shell and cap are securely held against separation.

Figs. 4 and 5 show the jacket and ring as applied to a socket which is of standard construction with the exception that its cap is strengthened. In these figures the shell, jacket and ring have been given the same reference

characters as in Figs. 1 and 3. The cap in Fig. 4 is generally designated 34 and as shown includes the nipple 35 and is provided with pockets 31 receiving the spring fingers 32 at the upper end of the shell 11.

5 Cap 34 is of the usual light gauge metal but is strengthened by having ribs or beads 37 pressed in the same whereby to make it more rigid so that a bending or twisting force on the nipple 35 will not collapse the cap. It will be apparent as 10 the jacket 17 and ring 18 have been screwed down or together to hold the cap and shell together the latter parts are securely connected and are not apt to be separated by a bending or twisting 15 force applied to nipple 35.

The shells are threaded at 38 to attachment of any suitable type of shade holder.

Having thus set forth the nature of my invention, what I claim is:

1. In an electric socket, a metal cap, a thin 20 metal shell partly telescoping with said cap, inter-engaging means on the shell and cap for detachably holding them in such relation, an external shoulder on the cap at one side of said telescoping joint, an external shoulder on the shell at the 25 other side of and in substantially spaced relation to said joint, a metal ring including a portion engaging the shoulder of the cap, a metal jacket enclosing a substantial portion of the shell and including a portion engaging the external 30 shoulder of the shell, and said jacket and ring screw threaded together to draw their portions tight against the shoulders of the cap and shell whereby to protect the shell and hold the latter and the cap against casual separation. 35

2. In an electric socket, a metal cap, a thin metal shell partly telescoping with said cap, one of said cap and shell having small pockets therein, spring fingers on the other of said cap and shell and entering said pockets to detachably 40 hold the cap and shell in such telescoping relation, an external shoulder on the cap at one side of said telescoping joint, an external shoulder on the shell at the other side of and in substantially spaced relation to said joint, a metal ring 45 including a portion engaging the shoulder of the cap, a metal jacket enclosing a substantial portion of the shell and including a portion engaging the external shoulder of the shell, and said jacket and ring screw threaded together to draw their 50 portions tight against the shoulders of the cap and shell whereby to protect the shell and hold the latter and the cap against casual separation.

3. In an electric socket, a metal cap, a thin metal shell partly telescoping with said cap, an 55 external shoulder on the cap at one side of said telescoping joint, an external shoulder on the shell at the other side of and in substantially spaced relation to said joint, a metal ring including a portion engaging the shoulder of the cap, a metal jacket enclosing a substantial portion of the shell and including a portion engaging the external shoulder of the shell, said jacket and ring screw threaded together to draw their portions 60 tight against the shoulders of the cap and shell, 65 said jacket having an opening therethrough for the passage of switch operating means to the interior of the socket, and means preventing turning of said jacket relative to said switch operating means.

HARVEY HUBBELL, JR.
